[57] CLAIM

The ornamental design for a heating element for use in residences preferably of baths and boarding to be placed standing free before a wall, as shown and described.

DESCRIPTION

FIG. 1 is a front elevation view of a heating element for use in residences preferably of baths and boarding to be placed standing free before a wall, showing our new design;

FIG. 2 is a left side elevation view thereof, the opposite side being a mirror image of that shown;

FIG. 3 is a rear elevation view thereof;

FIG. 4 is a top plan view thereof; and,

FIG. 5 is a bottom plan view thereof.
